UNITED STATES PATENT OFFICE.

HARRY CHAPLIN PERCY, OF NATCHITOCHES, LOUISIANA.

RESILIENT WHEEL.

1,085,700.

Specification of Letters Patent. Patented Feb. 3, 1914.

Application filed April 30, 1912. Serial No. 694,178.

To all whom it may concern:

Be it known that I, HARRY C. PERCY, a citizen of the United States, residing at Natchitoches, in the parish of Natchitoches 5 and State of Louisiana, have invented a new and useful Resilient Wheel, of which the following is a specification.

The invention relates to improvements in resilient wheels for automobiles and other 10 vehicles.

The object of the present invention is to improve the construction of resilient wheels, and to provide a simple, efficient and highly resilient wheel of comparatively 15 inexpensive construction, designed to dispense with pneumatic tires, and equipped with cushioning-springs, adapted to absorb the shock, jars and vibrations resulting from irregularities in the road and other 20 causes.

With these and other objects in view, the invention consists in the construction and novel combination of parts hereinafter fully described, illustrated in the accompanying 25 drawings, and pointed out in the claims hereto appended; it being understood that various changes in the form, proportion, size and minor details of construction, within the scope of the claims, may be resorted to 30 without departing from the spirit or sacrificing any of the advantages of the invention.

In the drawings:—Figure 1 is a side elevation of a resilient wheel, constructed in 35 accordance with this invention, one of the side plates being broken away. Fig. 2 is central longitudinal sectional view on the line 2—2 of Fig. 3. Fig. 3 is a transverse sectional view on the line 3—3 of Fig. 1. 40 Fig. 4 is a detail sectional view on the line 4—4 of Fig. 1. Fig. 5 is a detail longitudinal sectional view on the line 5—5 of Fig. 3. Fig. 6 is a detail view, illustrating the construction of the central portion of the 45 side spokes.

Like numerals of reference designate corresponding parts in all the figures of the drawings.

In the accompanying drawings in which 50 is illustrated the preferred embodiment of the invention, the wheel is equipped with a hub 1, preferably in the form of a rectangular sleeve provided with a central opening 2 and having its terminals 3 reduced to 55 receive centrally arranged side plates 4.

The hub, which is adapted to be arranged on the spindle of an axle, may have its bearing portion constructed in any preferred manner, and the side plates 4, which are circular, are provided with central openings 5, and the reduced ends of the hub are headed at the outer faces of the side plates to retain the same, in place against the shoulders formed by the reduction of the terminals of the hub, but any other suitable 60 fastening means may of course be employed. The hub, which is constructed of suitable metal, has flat outer faces, and it is connected with a metallic rim 6 by central and side springs. 70

The rim 6 may be either rigid or locally yieldable and the central springs, which are arranged in an annular series in the medial plane of the wheel, constitute resilient spokes and are preferably constructed of a 75 single piece of resilient material, such as wire or rod metal, and the size and strength of the central and side springs will vary to suit the character of the automobile, motor truck, or other vehicle on which the wheel 80 is to be used. Each of the central springs or spring spokes is composed of two similar side branches connected at their inner ends by a straight portion 7, seated against the adjacent flat exterior side face of the hub, 85 as clearly illustrated in Fig. 2 of the drawings. The side branches of the central springs are curved outwardly from the corners of the hub and converge and meet at a point beyond and in spaced relation with the 90 hub to form an inner spring loop 8. The side branches of the central springs are contiguous and fit against each other adjacent to the corners of the hub, and they are tied or secured together by means of coils 9 of 95 wire wrapped around the contiguous portions of the side branches of the springs and securely holding the same against the hub. The side branches of each spring are also tied or connected together at the outer end 100 of the loop 8 by binding coils 10, which are wrapped around the said side branches. Any other suitable means, however, may be employed for securing the contiguous 105 portions of the springs together.

The side branches of the central spring are curved outwardly to form intermediate spring loops 11 of approximately circular form, the loops 11 being arranged in an annular series around the wheel midway be- 110

tween the rim and the hub and having their adjacent portions fitted together and tied or connected by binding coils 12. The outer portions 13 of the central springs are approximately semi-circular and are reversely curved and are centrally tied or connected by binding coils 14. By fitting the loops of the springs against one another and securing them together, the said springs mutually support each other and co-act in absorbing shocks, jar and vibrations and distributing the strain throughout the annular series of the central springs or spring spokes. The outer curved portions 13 of the adjacent springs are connected by arcuate portions 15, fitted against the inner periphery of and suitably secured to the rim 6. By connecting the curved outer portions of the adjacent springs, an annular series of outer loops 16 is provided. Also the inner connected portions 17 of the side branches of the spring are arcuate and are curved in the opposite direction so that the side branches of the adjacent springs coöperate to form an annular series of loops 18. These spring loops gradually increase in size from the hub to the rim of the wheel, the loops 8 being smaller than the loops 18, and the loops 11 being of greater length than the loops 18 and 30 smaller than the outer loops 16. The outer arcuate connecting portions 15 are connected with and braced by an outer annulus 19, consisting of a ring of wire, or other suitable material and secured to the connecting portions 15 by soldering, brazing, sweating or any other suitable means.

The side springs, which are arranged in an annular series, are located at the central portion of the wheel between the side plates 40 4, and are connected with the rim by radially arranged spokes 20, having a slight lateral inclination in opposite directions and suitably secured at their outer ends to the rim 6, and provided at their inner ends 45 with terminal hooks 21, which engage and embrace the annular series of side springs at the peripheral portions thereof. Each of the series of side springs consists of an inner loop 22 and outer reversely curved portions 23, which are connected with the side branches of the adjacent springs by arcuate peripheral portions 24. The inner loops 22, which are of the same configuration as the loops 8 of the central springs, have 55 straight inner portions 25, which fit against the side faces of the hub in spaced relation with the straight portions 7 of the central springs. The loops 22 are tied or connected together at their contiguous sides by binding coils 26, and the sides of each loop are connected at the outer portion thereof by a binding coil 27. Each end of the series of side springs are braced or reinforced at the periphery by an annulus 28, consisting of a ring 65 of wire or other suitable material, arranged

concentric with the outer annulus 19 in a plane parallel with the same. The hooks 21 extend around the inner annulus and the arcuate portions of each of the side springs and are secured to the same by soldering, brazing, or other suitable means to prevent the inner ends of the spokes from slipping on the side springs. The terminals of the wire of each of the series of springs and each annulus are connected by coils 29 and are soldered, brazed, or otherwise secured together. The annular series of side springs are arranged between the central series and the side plates in spaced relation with the same, and they are substantially of the same diameter as and are practically concealed and protected by the parallel side plates.

The wheel is equipped with a metallic tire 30, secured on the rim by means of tire bolts 31, and cotter pins 32, or any other suitable means may be employed for securing the nuts 33 on the inner ends of the bolts 31.

What is claimed is:—

1. A resilient wheel comprising a hub, a rim, an annular series of central springs arranged in the medial plane of the wheel and extending from the rim to the hub, annular series of side springs located at the central portion of the wheel and at the end portions of the hub in spaced relation with the central springs, the springs of each set being bent to form loops, which are arranged to mutually support one another, and spokes extending from the side springs to the rim.

2. A resilient wheel comprising a hub, a rim, an annular series of central springs arranged in the medial plane of the wheel and extending from the hub to the rim, an annular series of side springs located at the central portion of the wheel in spaced relation with the central springs, each set of springs being bent to form loops increasing in size from the hub outwardly and the loops of each set contacting with and mutually supporting one another, and spokes extending from the side springs to the rim.

3. A resilient wheel comprising a hub, a rim, an annular series of central springs arranged in the medial plane of the wheel and extending from the hub to the rim, annular series of side springs located at the central portion of the wheel in spaced relation with the central springs, said spring being bent to form loops and the loops of each set successively increasing in size from the hub toward the rim and the loops of each set being arranged to mutually support one another, spokes extending from the side springs to the rim, and side plates mounted on the end portions of the hub and located beyond and in spaced relation with the side springs.

4. A resilient wheel including a hub, a rim, and an annular series of springs, each spring being composed of two side branches bent to form inner loops mounted on the

hub, intermediate loops, and reversely extended outer portions, which are connected to the said rim.

5. A resilient wheel including a hub, a rim, and an annular series of springs, each spring being composed of two side branches bent to form inner loops mounted on the hub, intermediate loops, and reversely extended outer portions connected to the rim, 10 the outer extended portions of the adjacent springs being also connected to form outer loops.

6. A resilient wheel including a hub, a rim, and an annular series of springs, each 15 spring being composed of two side branches bent to form inner loops mounted on the hub, intermediate loops, and reversely extended outer portions connected to the rim, the side branches of the adjacent springs 20 being secured together and the loops being arranged to mutually support one another.

7. A resilient wheel including a hub, a rim, and an annular series of springs, each 25 spring being composed of two side branches and bent to form inner loops mounted on the hub, intermediate loops, and reversely extended outer portions connected to the rim, the extended outer portions of the adjacent 30 springs being also connected to form an annular series of outer loops and the side branches of the adjacent springs being secured together and forming a series of loops located between the inner and intermediate loops.

35. 8. A resilient wheel comprising a hub, a rim, and an annular series of springs constituting spokes and consisting of inner loops seated against and surrounding the hub, intermediate oblong loops extending around 40 the wheel and connected together at their ends, and bowed outer portions secured to the rim and forming an outer annular series of loops, and means for securing the adjacent sides of the inner loops together, where- 45 by the springs are retained on the hub.

9. A resilient wheel including a hub, a rim, and an annular series of springs, each 50 spring being composed of two side branches bent at their inner ends contiguous to the hub to form inner loops and connected together at the outer portions of the same, said

side branches being oppositely bowed or bent beyond the inner loop to form an intermediate loop and having their outer ends secured to the rim and the said side branches 55 being connected together at a point between the rim and the intermediate loop, the intermediate loops of the springs being connected together and mutually supporting one another. 60

10. A resilient wheel including a hub, a rim, an annular series of springs, each spring consisting of two side branches bent to form inner and intermediate loops and having reversely extended outer portions, said springs 65 being also provided with outer arcuate portions fitted against the rim and connecting the reversely extended outer terminal portions of adjacent springs and the loops being arranged to mutually support one another. 70

11. A resilient wheel including a hub, a rim, an annular series of springs, each spring consisting of two side branches bent to form inner and intermediate loops arranged to mutually support one another, said springs 75 having reversely extended outer portions and being also provided with curved outer portions fitted against the rim and connecting the said reversely extended portions of adjacent springs, and an annulus arranged 80 within the rim and connecting the outer portions of the springs.

12. A resilient wheel including a hub, a rim, an annular series of central springs arranged in the medial plane of the wheel and 85 extending from the hub to the rim, separate sets of side springs spaced from the central springs and located at the central portion of the wheel, each set including inner loops seated against the hub and fitting against 90 one another, reversely extended outer portions, and peripheral connecting portions, and spokes connected at their inner ends with the side springs and extending therefrom to the rim. 95

In testimony, that I claim the foregoing as my own, I have hereto affixed my signature in the presence of two witnesses.

HARRY CHAPLIN PERCY.
